WORKHOLDER

John R. Tillman, Bridgeport, Conn., assignor to
The Bullard Company, a corporation of Connecticut

Application August 11, 1932. Serial No. 628,312

14 Claims. (Cl. 279—106)

This invention relates to a work holder or fixture of the type used for metal working apparatus such as lathes, grinders, milling machines or the like.

It is among the prime objects of the present invention to provide a novel, simple, efficient and effective work holder which, while being adapted for manual operations, is particularly designed for power operation.

10 Another object is to provide a work holder which will positively retain the work and which after operated to work retaining position will not slip therefrom nor transmit the holding pressures to the operating mechanism.

15 A further object is to provide a fixture for retaining hollow cup-like bodies and is particularly designed to internally grasp such bodies, leaving the full outer surface thereof exposed for metal working operations.

20 A further object is to provide a work holder which is so arranged as to automatically insure the proper alignment of the work with the holder so that apertures of the work will be properly grasped and secured by the holder.

25 A further object is to provide a work holder which includes a reciprocating body having radially moving means which automatically operate in conjunction with the reciprocation of the body so as to be extended therefrom to grasp 30 the work and to move thereafter with the body to secure the work against the face plate of the work holder.

35 A further more specific object is to provide a work holder for holding piston blanks, the structure providing a self-contained device which constitutes a single, simple, unitary structure for firmly securing the blanks by engagement through their gudgeon pin apertures.

40 For purpose of illustration, the invention is disclosed as formed to accommodate a piston blank. In this particular form of the invention, the device consists of a rotatable face plate carried for rotation with a conventional type work spindle. Associated with the face plate is 45 a reciprocable body adapted to be actuated by crank actuating members which in turn are actuated by a longitudinally extending actuating rod.

45 An important feature of the invention is the fact that the rod to crank relationship is such that after the parts are operated, strains will not pass back through the cranks to the rod. This is made possible by a particular cam surface design as will be hereinafter discussed. The upper 55 end of the actuating rod has a lost-motion

connection with pivoted toggle-like work engaging arms which in the present embodiment of the invention are adapted to be received within the gudgeon pin openings of a piston blank. Another feature of the invention is the provision of an arm operating means which, as in the case of the crank operator, will not transmit holding strains back through to the operating mechanism. The illustrative embodiment of the invention also includes camming end surfaces which are adapted to be engaged by the gudgeon pin bosses of the blank. In the operation of this form of the invention, the operating rod may be spring urged in a releasing direction. Thus, the body actuating cranks are normally held in a manner to retain the body in an inward position against the tension of body springs and the upper ends of the pivoted toggle-like engaging arms are forced apart at the entrance therebetween of a forcing wedge moved with the operating rod. The rod is adapted to move upwardly against the tension of its spring by a cam which movement releases the inner end of the body holding cranks, thus releasing the body and allowing it to move outwardly under the influence of the body springs and thus the engaging arms are moved, relieving the pressure on the work piece. Further movement of the operator will cause the upper ends of the arms to move together, thus releasing the gudgeon pin apertures. At the same time, spring-urged ejector pins act to kick out the work from the work holder.

With reference to the drawing:

Fig. 1 is a vertical sectional view of one specific embodiment of the present invention.

Fig. 2 is a side elevation taken at right angles to the plane of the section of Fig. 1, and

Fig. 3 is a top plan view.

Referring more particularly to the drawing, a conventional type of work spindle is indicated by the numeral 10. Suitable driving means are provided for the work spindle as indicated by the gear 11 which is keyed thereto and secured by a securing nut 12. Obviously, this structure is merely a representative of conventional work spindle and the invention is not confined to any particular structure thereof.

The spindle is illustrated as being tubular and being provided at its lower end with an enlarged socket 13 which is adapted to receive a spring 14. The latter encircles the lower end of an operating rod 15 having an enlarged head 16, against which the spring 14 thrusts, thus normally urging the rod in a downward position. The head 16 also acts to receive the operating

thrust from a cam or similar operating mechanism such as indicated at 17.

The head 18 of the spindle has secured thereon as by bolts 19 a work fixture face plate 20. 5 The head 18 and the face plate 20 are cooperatively recessed to provide ample space therebetween for the mechanism of the work holder as will be hereinafter described.

The upper end of the operating rod 15 has 10 secured thereon as by the threads illustrated, an operating head 21 opposite sides of which are cut away to provide grooves 22 which permit the inward movement of the lower ends of the body holding crank when the rod is elevated. The 15 grooves 22 terminate in outwardly extending cam surfaces 23 which in the normal downward position of the operator rod engage and hold outwardly the lower end of the body holding cranks 24, which cranks are pivoted in pintles 25 carried by the face plate 20. This position of the 20 cranks is illustrated in Fig. 1. It will be noted that the angle of the surface 23 is less than the angle of repose. It is important that the cam be so designed since the result will be that after 25 operation thereof, to move the cranks, back pressure tending to reverse the movement of the cranks will not be transmitted as a force acting to move the operating rod. Thus, it will be noted that the rod and its spring will not be under 30 the work holding strains and after movement thereof to operate the parts, no continued force will be required to keep the parts in work holding position.

The cam-like cranks 24 are of general semi-circular configuration being provided with inwardly extending upper ends having projections 26 which upon rocking movement of the cranks engage a flange 27 of a cylindrical shell-like body 28. As illustrated, body springs 29 are provided 40 mounted within recesses within the flange 27 and bearing against the head 18 of the spindle, thus normally urging the body upwardly. Across the upper end of the body 28, a pin 30 extends and forms a pivotal support for a pair of gudgeon 45 pinion aperture engaging arms 31, each of which are provided with right angularly extending nose pieces 32 which upon outward movement of the upper end of the rod, are adapted to engage the gudgeon pin openings 33 of the work piece 34. 50 With the operating rod in downward position, it will be noted that the upper ends of the arms 31 are moved outwardly and retained in that position by interposition therebetween of a cross-bar 35 which extends between the bifurcated portions 36 of the outward extension of the operating rod head 21. It is important to note that after initial inward movement of the bar 35 which cams the nose pieces outwardly, the bar moves in behind the flat inner surfaces of the arms, its 60 flat sides lying parallel therewith. Thus, inward pressure of the nose pieces will not tend to cam the bar 35 and thus no holding strains will be transmitted therethrough to the operating bar. The outward extension also carries a cross-bar 65 37 which upon upward movement of the operator engages between the lower tapered end 38 of the arm 31 and thus moves them apart, retracting the nose pieces 32 so as to withdraw them from the gudgeon pin aperture. 70 It will be noted that the face plate 20 extends upwardly to form a housing for the body member, the side pieces thereof terminating in camming points from which the end wall sweeps downwardly to form camming surfaces 41. In 75 the center of the end portion 42 spring urged

ejecting pins having tapered points are provided. This arrangement is such that the operator need not be careful to place the piston blank upon the work holder with the gudgeon pins in alignment with the noses of the arms. Regardless of the relative position of the parts, it will be noted that by the inward thrust of the work, it will be guided by the pin bosses which by striking the camming surfaces 41 will rotate the work until the bosses are in alignment with the noses of the arms. This feature of the invention insures rapid and accurate placing of the work on the work holder.

Another feature of the invention is that the work holder may be operated manually regardless of the action between the cam 17 and the head 16. This is illustrated in Figs. 2 and 3. The head 21 of the operating rod is provided with a rack surface 43 preferably at right angles to the grooves 22. Meshing with the rack 43 is a pinion 44 mounted upon a transverse shaft 45 as shown in Fig. 2. The shaft terminates with a suitable operating head such as shown at 46, it being obvious that by the application of a crank thereto, the shaft may be rotated, thereby rotating the 100 pinion which by engagement with the rack correspondingly reciprocates the operating rod so that its operations are not wholly dependent upon automatic operating means.

In the operation of the device commencing 105 with the parts in position as illustrated in Fig. 1, it will be noted that by movement of the cam 17 it will engage the head 16 upwardly thrusting the rod 15 against the tension of the spring 14. Such upward movement of the rod will move the 110 head 21 upwardly whereby its cam surfaces 23 will release the outward thrust on the lower end of the crank 24 which lower ends will move inwardly to be received in the groove 22, thereby causing a rocking movement of the cranks on 115 their pintles 25 so that the upper end 26 releases the flange 27 of the body 28. The body will move slightly upward under the influence of the springs 29, it being only necessary that such movement is sufficient to release the inward pressure by the nose pieces 32 in the gudgeon pin apertures. Further upward movement of the rod 15 will cause the withdrawal of the bar 35 from 120 between the upper ends of the arms 31 whereby they are free to move inwardly which movement 125 will be subsequently caused by the continued upward movement of the rod when the cross-bar 37 engages between the lower end of the arms 31 thus moving them apart and thus withdrawing inwardly the nose pieces 32. It will, of course, be 130 noted that an elongated aperture is provided in the head piece of the operating mechanism so that such movement may be had without disturbing the pin 30 of the cross arms. At the end of the upward movement of the rod, it will 135 be noted that the ejector pin 47 carried by the end of the head of the operating mechanism will move outwardly to strike the inner end of the work piece 34 thus kicking it outward which movement will be aided by the outward thrust of the spring 140 urged ejector members 42.

When the work holder is to be loaded the work piece is moved axially over the work holder, its registration being insured by the camming action of the surfaces 41 whereby the gudgeon pin apertures are caused to automatically be aligned with the direction of outward movement of the nose pieces 32 as heretofore described. With the work piece in this position, the downward movement of the operating rod will first cause the bar 37 to 150

- be removed from between the inner ends of the arms, thus permitting them to be moved outwardly by further movement of the rod- cross-bar 35 of which will enter between the upper ends of the arms, thus forcing them outwardly. With the arms thus forced outwardly with the noses 32 in the gudgeon pin apertures, it will be seen that further movement of the rod will cause the parts to assume the position of Fig. 1. During such movement, the lower ends of the cranks are forced outwardly, thus moving inwardly their upper ends, which rocking movement causes the under surface of the end 26 to move downwardly, whereby they engage the upper surfaces of flange 27, moving the body downwardly, against the tension of its spring 29, which movement carries with it the cross-arms whereby their lower surfaces engage the work and move it down for firm securement against the face-plate 20.
- Having thus described the structure and operation of one specific embodiment of the present invention, it will be understood that the invention is not limited to the specific application or structural embodiment herein presented. Obviously, the work holder may be used in connection with various parts with various types of metal-working machines, and the invention is not even limited to its application to metal-working machines. It is further obvious that the invention is not limited to a structure specifically designed for the securing of a piston blank since it is within the scope of the invention to be applicable to various types of work holding requirements.
- Having thus described my invention, what I claim is:
1. In a work holder, the combination of an axially moving body, a pair of work-engaging arms pivotally mounted within the body, their ends being adapted to extend through the walls of the body, and means for axially moving the body, said means being adapted to cause pivotal movements of said arms.
  2. In a work holding fixture, the combination of an axially movable cylindrical body, a pair of pivoted arms supported thereto, an operating means for said arms and body and lost-motion connections between said operating means and said arms, whereby said operating means will reciprocate said body axially and independently thereof move said arms.
  3. In a work holder, the combination with a body adapted to receive the work thereabout of extending side pieces for said body having cam ends adapted to engage inward extensions of a work piece so as to rotate the work piece into predetermined alignment with said body.
  4. In a work holder, the combination with a body adapted to receive the work thereabout of extending side pieces for said body having cam ends adapted to engage inward extensions of a work piece so as to rotate the work piece into predetermined alignment with said body, and means to reciprocate said body.
  5. In a work holder, the combination with a body adapted to receive the work thereabout, of extending side pieces for said body having cam ends adapted to engage inward extensions of a work piece, so as to rotate the work piece into predetermined alignment with said body, and spring urged ejector pins carried by said side pieces.
  6. In a work holder, a reciprocable operating means, a body, means to reciprocate said body by said operating means, a pair of arms pivotally mounted with said body, a lost-motion connection between said arms and said operating means independent of said means to reciprocate said body, whereby movement of said operating means will cause the successive reciprocation of said body and pivotable movement of said arms.
  7. In a work holder, the combination of a reciprocable body, a pair of pivoted arms carried by said reciprocable body, an operating means for said reciprocable body, a cross-bar carried by said operating means, said cross-bar being arranged to engage said arms to move them to work operating position.
  8. In a work holder, the combination of a reciprocable body, a pair of pivoted arms carried by said reciprocable body, an operating means for said reciprocable body, a pair of cross-bars carried by said operating means, one of said cross-bars being arranged to engage said arms to move them to work operating position and another of said cross-bars adapted to move said arms to work disengaging position.
  9. In a work holder, the combination of a reciprocable body, a pair of pivoted arms carried by said reciprocable body, an operating means for said reciprocable body, a cross-bar carried by said operating means, said cross-bar being arranged to engage said arms to move them to work operating position and means to prevent said arms from moving said cross-bar.
  10. In a work holder, the combination of a reciprocable body, a pair of pivoted arms carried by said reciprocable body, an operating member for said reciprocable body, a pair of cross-bars carried by said operating means, one of said cross-bars being arranged to engage said arms to move them to work operating position and another of said cross-bars adapted to move said arms to work disengaging position, and automatic means to move said operating member.
  11. In a work holder, the combination of a reciprocable body, a pair of pivoted arms carried by said reciprocable body, an operating member for said reciprocable body, a pair of cross-bars carried by said operating means, one of said cross-bars being arranged to engage said arms to move them to work operating position and another of said cross-bars adapted to move said arms to work disengaging position, and manual means to operate said operating member.
  12. In a work holder, the combination of a reciprocable body, a pair of pivoted arms carried by said reciprocable body, an operating member for said reciprocating body, a pair of cross-bars carried by said operating means, one of said cross-bars being arranged to engage said arms to move them to work operating position and another of said cross-bars adapted to move said arms to work disengaging position, and manual and automatic means to operate said operating member.
  13. In a work holder, the combination of a reciprocable body, a pair of pivoted arms carried by said reciprocable body, an operating member for said reciprocable body, a pair of cross-bars carried by said operating means, one of said cross-bars being arranged to engage said arms to move them to work operating position and another of said cross-bars adapted to move said arms to work disengaging position, and spring means for normally urging said operating means to work engaging position.
  14. In combination with an axially rotatable tubular work spindle, a face plate carried thereby, a reciprocable body mounted within said face

plate, a pair of arms carried by said reciprocable body and reciprocable therewith, a longitudinally extending operating rod through said spindle, spring means for normally urging said operating rod in inoperative position, cam means movable by said rod to move said body downwardly, and

lost-motion connection between said arms and said rod whereby downward movement of said rod will cause said arms to engage a work piece, and means on said body to automatically insure alignment of a work piece with said arms.

JOHN R. TILLMAN.
